(57) **CLAIM**

We claim the ornamental design for the ball, as shown and described.

DESCRIPTION

FIG. 1 is a perspective view of the ball showing our design;
FIG. 2 is a front end view thereof;
FIG. 3 is a rear end view thereof;
FIG. 4 is a bottom plan view thereof;
FIG. 5 is a top plan view thereof;
FIG. 6 is the left side elevation view thereof, the right side elevation view being a mirror image.
